SEPARABLE BELT BUCKLE

Milton Brock, Bayside, N. Y.

Application November 5, 1951, Serial No. 17,290

Term of patent 3½ years

(Cl. D17—1)

To all whom it may concern:

Be it known that I, Milton Brock, a citizen of the United States and a resident of Bayside, county of Queens, Long Island, State of New York, have invented a new and original and ornamental Design for a Separable Belt Buckle, of which the following is a specification, reference being had to the accompanying drawings, forming part hereof and in which:

Fig. 1 is a front elevational view of my separable belt buckle with the elements thereof separated, showing my new design.

Fig. 2 is a front elevational view with the elements of Fig. 1 connected together.

Fig. 3 is a top edge elevational view.

I claim:

The ornamental design for a separable belt buckle, substantially as shown.
MILTON BROCK.
